Patented Dec. 30, 1975

238,272

SUPPORT MEMBER FOR USE WITH SIGNS, SHELVES, PARTITIONS AND THE LIKE

Irving W. Shell, 442 W. Wellington,
Chicago, Ill. 60657

Filed Jan. 28, 1974, Ser. No. 437,423

Term of patent 14 years

Int. Cl. D25—01

U.S. Cl. D13—6

FIG. 1

FIG. 2

FIG. 3

FIG. 4

FIG. 1 is an end elevational view of a support member for use with signs, shelves, partitions and the like showing my new design;

FIG. 2 is a fragmentary side elevation view;

FIG. 3 is a fragmentary top plan view;

FIG. 4 is a fragmentary bottom plan view;

FIG. 5 is a fragmentary perspective view; and

FIGS. 2 through 5 are fragmentarily shown to indicate indeterminate length.

I claim:

The ornamental design for a support member for use with signs, shelves, partitions and the like, as shown and described.
